FLOW VALVE

Filed Dec. 11, 1933

UNITED STATES PATENT OFFICE

2,072,435

FLOW VALVE

James W. Taylor, San Antonio, Tex.

Application December 11, 1933, Serial No. 701,793

5 Claims. (Cl. 103—233)

My invention relates to flow valves to be employed at different stages along the eduction tube where air or gas pressure is employed in raising liquid from deep wells. It pertains to those valves controlled by pressure differentials between the inside and outside of the eduction tube and is so designed as to eliminate objectionable features heretofore encountered in devices of this character. It is adapted for use where the pressure fluid is obtained directly from the well or where it is forced into the well by artificial pressure.

It is an object of the invention to provide a structure which will not be clogged by paraffin or similar residue from the well accumulating on the interior of the casing or on the upper surface of the liquid. Foreign matter, such as fragments of canvas or other packers and foreign material falling into the well, is frequently found floating on the surface of the liquid and tends to be carried into the valve when the liquid level reaches the level of the opening through the valve. I contemplate keeping the valve closed until the liquid level has passed below the valve.

I also contemplate so forming the inlet to the eduction tube that foreign matter settling in the tube will not clog the inlet opening from the valve to the tube.

I desire to provide a valve so constructed that its opening and closing differentials will not necessarily be the same so that the valve will open at different differential pressures than those at which it closes.

I desire to provide a flow valve which will remain closed where the liquid level has been lowered to a point adjacent the lower end of the tube and will not open to waste gas during the operation of the device.

Referring to the drawing herewith, Fig. 1 is a central longitudinal section through one of the couplings employed in the eduction tube, the coupling being equipped with my improved device.

Fig. 2 is an assembly view showing the well casing and the eduction tube in central longitudinal section.

Fig. 3 is a transverse section on the plane 3—3 of Fig. 1.

I have shown somewhat diagrammatically a well casing 1 having at its upper end a casing head 2 with a lateral inlet pipe 20 thereon through which fluid under pressure may enter into the well. The eduction tube 18 is to be understood as having a fluid tight fit through

the upper end of the casing head so that there will be no escape around the tube and above the inlet 20 for air.

Along the tube at different levels thereon I introduce special tubing couplings 3, said couplings being made with an interior thread 4 at the upper end and an exterior thread 5 at the lower end for connecting in the pump tube 18. At one side of the coupling is rigidly fixed a valve housing 6.

The valve housing 6 is made of any suitable material and securely welded to the exterior of the body as shown. In the housing is a valve member 7, which shuts off communication between the casing and tubing when it moves into the outlet 8 at the upper end of the housing. At its lower end, or bottom, the housing is closed to gas entry upwardly from that end by the plug 9 in the upper end of which a seat 10 is formed. The numeral 11 indicates a lateral gas entry, which is placed in this position in order to prevent the forcing of paraffin and the like into the valve housing when the device is being lowered into the well. It will be noted that the outlet 8 is so formed at its terminus as to divert gas flow through the valve housing downwardly as it passes into the flow pipe. This feature is to prevent the settling of sediment in the submerged valves when the well is being flowed from higher levels. For example, if the well is being flowed through valve 16, Fig. 2, sediment carried by the liquid would settle back into valve 17 where the outlet pointed upwardly or even horizontally. But experience has shown that with the outlet turned in a downwardly direction no trouble from this source is experienced.

In considering the construction of my valve certain factors must be considered. For instance, where a spring is used to hold it open, as has previously been the case in most similar devices, the pressure at which the valve closes will in every case also be the pressure at which it opens.

If the valve does not close until the pressure in the flow line is less by fifty pounds than the casing pressure, then it will open as soon as the pressure is again equalized within fifty pounds. Valves of this type operate fairly well where a large amount of liquid is being moved rapidly from the well under high pressure. However, once the liquid in the casing has been discharged and the operating fluid begins to escape from the well by entering the lower end of the flow pipe the pressure between the casing and the flow line becomes so near equalized that the spring actuated valve opens and permits the gas to es-

cape from the casing to the flow line through the upper valve.

For example, in Fig. 2, when the resistance to flow from the bottom of the tubing 19 to the 5 lowermost valve 17 becomes less than the spring pressure of the valve, then the valve opens; and when the lowermost valve opens and begins to admit gas to the tubing it soon brings the next valve above within range of its differential pressure and causes it to open. And this follows up until all valves open, which results in a heavy loss of the operating fluid.

From the foregoing, it will be seen that, while it is desirable to have the valve remain open until a comparatively high pressure differential has been established between the casing and tubing, it is necessary to hold the pressure at which the valve opens safely below the resistance offered to flow by the tubing between valves, under any and 20 all conditions.

There are four factors that enter into the operation of the valve: The weight of the member 7, Fig. 1, the contours of its upper and lower ends 12 and 13, the areas of the outlet 8 and the 25 lower seat 10. With the valve a given weight, the smaller the outlet 8, the higher will be the opening differential pressure after the valve is in its upper seat; and the larger the seat 10, the lower will be the pressure required to lift the 30 member 7 from the seat 10 and admit gas to the chamber 6.

With the member 7 resting on the seat 10, it is plain that a certain excess of pressure must be applied through the inlet 11 over that in the tube 35 and above the valve before the member would leave the seat 10 and admit gas to the interior of the chamber 6; this will be called "pick-up differential". The pressure at which the valve shuts off gas flow by being carried to the upper 40 seat 8, will be called "closing differential", and the pressure at which it drops by gravity from the seat 8 to admit gas to the tubing will be called "opening differential".

The "opening differential" is determined by 45 dividing the weight, in pounds, of the member 7 by the area, in square inches, of the outlet 8. The "pick-up differential", the pressure required to lift the member 7 from the seat 10 to admit gas to the housing, is determined by dividing the 50 weight of the member 7 by the area of the seat 10. The "closing differential" is determined by the taper of the head 13 on the member 7.

Thus it will be seen that the valve may be varied and controlled by the use of my invention with an exactness heretofore not found in devices of this character. Also it has been found that the gas inlets must be proportioned to the size of the tubing, i. e., the inlets must increase or decrease in the same ratio as does the cross- 60 sectional area of the tubing. For if the gas entry be too large, the volume of gas entering the tubing will set up a resistance so great in the pipe above the valve that the latter will not shut off flow, for the reason that the pressure differential necessary to its closing cannot be established. The greater the depth, the greater the gas pressure necessary to flow the well. Increased pressure means increased density; and increased 65 density means increased flow through a given size orifice, even though the pressure differential remains the same. In other words, it is necessary that the volume of operating fluid flowing through the valve under any and all conditions 70 be known, at least to a reasonable degree of cer-

tainty; and this is easily arrived at when the correct formula is used.

Fig. 2 represents the well being flowed by admitting compressed air or gas to the casing 14 through the pipe 20. The liquid has been lowered in the casing to a point below the lowermost valve 17. The upper valve 15 has closed due to the fact that the pressure in the flow line at this point has become less, by the "closing differential" pressure of the valve, than the pressure in 10 the casing. Member 16 is in operation and the well is flowing from this point.

Valve 17 has not yet opened from below to admit gas to the housing, for the reason that the casing pressure and the pressure in the tubing are 15 too nearly equal at this point for the valve 7 to be raised from the seat 10 at the instant the gas reaches it. For the weight of the valve 7 is concentrated on the seat 10; the weight of the liquid in the tubing, plus the resistance set up by the 20 gas flowing through member 16, are all pressing back against the valve 7 to hold it against the seat 10 and prevent flow through the valve housing. This means that the valve 7 will not move off the seat 10 until the liquid in the casing has 25 reached a level several feet below the valve. Thus, by the valve's remaining closed to flow until the liquid has passed the entry 11, floating foreign matter does not find its way into the housing but is forced around the lower end of the 30 tubing and out of the well. By regulating the inlet and the outlet from each valve and the taper on the end of the valve, I am enabled to obtain accurate performance so that no gas will be wasted.

When in operation, the valves automatically close as the liquid is lowered in the well. Should the well be emptied to a point where the air or gas enters with the liquid at the bottom of the tubing, then all valves will have closed and will 40 remain so as long as the well is flowed from this point. It will be seen, however, that if for any reason the liquid should rise in the well to a point where the gas would be shut off from entering the lower end of the flow line, flow would 45 cease. But as soon as the liquid coming into the well rises in the tubing to within a predetermined distance of the lowermost valve, said valve will open by gravity and admit gas to the tubing to continue the flow. And what applies to one valve 50 applies to all valves.

Where it is desired to limit the flow, the well may be flowed from any point where a valve is located, by merely restricting the volume of operating fluid entering the casing.

The extreme simplicity and durability of the present invention as a whole will be noted. There are no springs or small parts to get out of order, it is easily and cheaply manufactured, and has proved remarkably efficient in use. It adapts 60 itself to regulation as to opening and closing differentials so that waste of pressure fluid may be avoided.

Having described the invention, what I claim is:

1. A flow valve for well tubing including a tubular body having a female thread in the upper end adapted to engage the tubing thread, a male thread on the lower end thereof adapted to engage the tubing coupling, a valve housing attached vertically to the exterior of said body, an entry in the side wall at the lower end of said housing, an outlet in the upper end thereof, said outlet terminating in a downwardly directed 70 passage into said body, valve seats in said entry 75

and said outlet, and a valve disposed between said inlet and outlet to engage either of said seats to control the flow of fluid therethrough.

2. A flow valve for well tubing including a tubular body, a valve housing attached vertically to the exterior of said body, a lateral entry adjacent the lower end of said housing, an outlet to said body at the upper end thereof, a gravity operated valve of predetermined weight disposed between 5 said inlet and outlet to control the flow of fluid therethrough, the lower end of said valve being formed on an obtuse taper whereby the weight of said valve will hold it seated to prevent fluid entry into said inlet until the liquid has reached a predetermined level in the well below said inlet.

3. A flow valve for eduction tubes including an elongated housing on the side of said tube, a lateral entry adjacent the lower end of said valve, a downwardly inclined passage from said housing 10 to said tube, a valve seat in said passage, a valve member of predetermined weight shaped to fit within said housing and movable by fluid pressure

to control said entry and said passage, the lower end thereof being more obtusely tapered than the upper end for the purpose stated.

4. A method of flowing liquid from the tubing in wells comprising depressing, by means of gaseous fluid pressure, the level of liquid in the well outside said tubing, admitting gaseous fluid under pressure to said tubing at successively lower levels, and opening the entrance for said fluid to said tubing only when the level of liquid in said well 10 has fallen below the respective entrances for said fluid to said tubing.

5. In the flowing of liquid from a well tubing by means of air or gas, the improvement consisting of depressing the level of liquid in the well outside said tubing and opening up inlets for air to said tube at successively lower levels, only after the level of said liquid has passed below the respective inlets, and maintaining said liquid level below any of said open inlets. 20
